UNITED STATES PATENT OFFICE.

THEODORE S. WILKIN, OF MILWAUKEE, WISCONSIN.

SAW-MILL CARRIAGE.

SPECIFICATION forming part of Letters Patent No. 437,957, dated October 7, 1890.

Application filed August 6, 1888. Serial No. 282,050. (No model.)

To all whom it may concern:

Be it known that I, THEODORE S. WILKIN, of Milwaukee, in the county of Milwaukee, and in the State of Wisconsin, have invented 5 certain new and useful Improvements in Saw-Mill Carriages; and I do hereby declare that the following is a full, clear, and exact description thereof.

My invention relates to saw-mill carriages, 10 and will be fully described hereinafter.

In the drawings, Figure 1 is a vertical transverse section on line 1 1, Fig. 2, of a saw-mill carriage embodying my invention. Fig. 2 is a section on line 2 2, Fig. 1. Fig. 3 is an elevation of one axle-box partly broken away; 15 and Fig. 4 is a section on line 4 4, Fig. 3.

A is a head-block of the carriage, and B B are the longitudinal beams of the same.

C are the axle-boxes, and D are links, each 20 of which passes through a slot in the beam B and is pivoted at one end in a housing F in the under side of the head-block by a bolt c, and at its other end is pivoted to one of the boxes C, this end fitting between ears a a, 25 that receive the pivot-bolt b. Collars d prevent the boxes C from sliding inwardly on the axle G, and a collar f and nut g confine the outer wheel G' on each axle. The journals of the axle turn loosely therein in collars f, 30 and these collars are formed with recesses f'—one on each side—and the fingers i of a spanner j project into them. The spanner j is carried by a rock-shaft K, which is journaled in brackets L, that are bolted to the beam B, 35 and this shaft carries a spanner for each axle, as well as a lever M, by which it (the shaft) is operated.

The object of my invention is to facilitate 40 the shifting of the head-block independently of the axles, and it operates as follows: The axles form the fulcrum of the lever M, and the inner wheels G² are sheaved to fit their rail, and therefore if the lever M be drawn in the direction indicated by the arrow, Fig. 1,

it will draw the carriage with it as far as the 45 links D will permit, inclining the links, as shown in Fig. 1, and if the lever be thrust back it will advance the carriage.

Flanged shoes P are secured to the under side of beams B by bolts R, which flanged 50 shoes inclose the sides of the upper portion of the axle-boxes C and by contact therewith serve to relieve the links D of undue strain.

Having thus fully described my invention, what I claim as new, and desire to secure by 55 Letters Patent, is—

1. The combination, with a saw-mill carriage, of axle-bearings movably connected thereto by links pivoted to the carriage and to the bearings, a rock-shaft journaled upon 60 the carriage and operatively connected with one end of one of the truck-axles, and an upwardly-extending hand-lever carried by said shaft, whereby the movements of the operating-lever are fulcrumed upon the truck-axle 65 and serve to move the carriage transversely thereon, substantially as described.

2. The combination, with a saw-mill carriage, of axle-bearings movably connected thereto by links pivoted to the carriage and 70 to the bearings, a rock-shaft journaled upon the carriage, an upwardly-extending hand-lever carried by said rock-shaft, recessed collars secured upon the truck-axles, and spanners mounted upon the rock-shaft and engaging 75 said collars, so as to constitute the fulcrums for the operating-lever in shifting said carriage laterally upon the bearings, substantially as set forth.

In testimony that I claim the foregoing I 80 have hereunto set my hand, at Milwaukee, in the county of Milwaukee and State of Wisconsin, in the presence of two witnesses.

THEODORE S. WILKIN.

Witnesses:

STANLEY S. STOUT,
GEO. M. CONWAY.
